UNITED STATES PATENT OFFICE.

WILLIAM H. WILDER AND FRED E. WHITE, OF GARDNER, MASSACHUSETTS, ASSIGNEES TO CENTRAL OIL & GAS STOVE COMPANY, A CORPORATION OF MAINE.

OVEN.

1,107,470.

Specification of Letters Patent.

Patented Aug. 18, 1914.

Application filed February 7, 1912. Serial No. 676,100.

To all whom it may concern:

Be it known that we, WILLIAM H. WILDER and FRED E. WHITE, citizens of the United States, residing at Gardner, Massachusetts, have invented certain new and useful Improvements in Ovens, of which the following is a specification.

Our present invention relates more especially to improvements in portable ovens designed for use in connection with oil and gasoline stoves, and has among others for its objects to provide an oven with a very simple and economical form of shelf and shelf support with a shelf free from projections and permitting free sliding of the dishes, and capable of being readily inserted and firmly held in position during use.

With these and other objects in view, the invention includes the novel features of construction and arrangement and combination of parts hereinafter described and particularly defined by the appended claims.

An oven constructed in accordance with our invention is illustrated in the accompanying drawings in which—

Figure 1 is a transverse vertical section through the oven, and Fig. 2 is a plan view of the bottom shelf.

Referring by reference characters to this drawing the numeral 1 designates an outer sheet metal case, preferably of rectangular form and having in the bottom an opening 2 to permit the entrance of the heated gases. The sides, top and back of the outer case are preferably lined with asbestos as indicated at 3, and within the case at the sides, back, and top is an inner lining of sheet metal indicated at 4, the top lining being arched as indicated at 4^a to avoid corners which would tend to retain cold air.

Lower and upper shelves are indicated at 5 and 5^a, and these shelves are composed of longitudinal bars *a* and *b* respectively, which are connected by and support the transverse rods *c* upon which the articles within the oven rest. The transverse bars *a* and *b* are formed of strips of sheet metal folded upon themselves, with the ends of the rods *c* clamped between said folded portions, the sheet metal being pressed down between the rods as indicated at *a'* and *b'* to hold the rods firmly in position.

Shelves have heretofore usually been supported by ledges or flanges projecting from the walls of the oven which is objectionable

as obstructing the flow of heated air at the sides of the oven and also provides corners for the collection of grease and dirt which are difficult to clean.

Our improved shelf is supported at the back by projecting two or more of the rods *c'* through openings in the back bar *b*, as indicated at *c''*, holes 4^e being provided in the back lining to receive these projected ends. The holes are preferably counter-sunk as shown by pressing or swaging the metal outward, to facilitate the entrance of the ends of the rods. The front bars *a* are folded into substantially L shape to provide a downwardly extending flange *a''* which drops into recesses or spaces *d'* between the two projections *d''* at the front. These projections are formed by inward bends in a vertically disposed strip *D* secured to the inner case or lining on each side in proximity to the door opening, there being one set of projections for the upper shelf and a corresponding set for the lower shelf. The strips are held in place by having their ends inserted in slits in the inner case or lining and their intermediate portions secured by rivets or like fastening devices.

By the foregoing construction a very simple and economical form of shelf and shelf support is provided, the shelf being free from projections and permitting free sliding of the dishes or other articles thereon due to the rods extending back from the doorway to the back wall parallel to the line of movement of the dishes, and the shelves are readily insertible and removable and firmly held in position during use.

To the lower shelf we secure a combined drip pan and deflector 6 which comprises a sheet of metal having upwardly turned ends bent over and around the outside rods of the shelf.

At the front of the oven and closing the front opening thereto we provide a door 7 of sheet metal which is hinged at its lower edge by hinges not shown which support it in a horizontal position when opened outward. The door is preferably provided with a handle 11^a pivoted at 11 and controlling a locking device 10^b, and also with one or more glass panes 14 held at their edges by flanges 15.

Having thus described our invention what we claim is:

1. An oven having recesses in the back

wall thereof, and a shelf comprising longitudinal cross bars at front and back and transverse rods connecting said cross bars, part of said rods being projected beyond the 5 rear cross bar to enter said recesses.

2. An oven having recesses in its back wall and lugs provided with vertical recesses on its sides near the front and a shelf having at the rear projections to enter said 10 recesses and at each front corner a vertically depending flange to enter the recesses in the lugs.

3. An oven having recesses in its back wall and lugs provided with vertical recesses on its sides near the front, and a shelf 15 comprising front and rear cross bars connected by transverse rods, part of said rods being projected beyond the rear cross bar to enter said recesses and said front cross 20 bar having a depending flange to enter the recesses of said lugs.

4. An oven having means carried by the back wall for supporting a shelf, sheet metal strips secured to the inner wall of the oven

near the front, said strips having inward 25 bends provided with vertical slots, and a shelf having its rear end supported by the back wall of the oven and having at the front a bar with a vertical flange having its ends seated in said vertical slots. 30

5. An oven having recesses in its back wall and lugs on its sides near the front provided with vertical recesses and a shelf comprising transverse rods and front and rear cross bars comprising strips of sheet 35 metal folded upon itself with the rods clamped between the folded portions, part of the rods being projected beyond the rear cross bar to enter said recesses, said front bar having a depending flange with its ends 40 seated in the recesses in the lugs.

In testimony whereof, we affix our signatures in presence of two witnesses.

WILLIAM H. WILDER.
FRED E. WHITE.
